A. E. WELLS.
STAIR CONSTRUCTION.
APPLICATION FILED NOV. 23, 1914.

1,189,414.

Patented July 4, 1916.

UNITED STATES PATENT OFFICE.

ARTHUR E. WELLS, OF TORONTO, ONTARIO, CANADA.

STAIR CONSTRUCTION.

1,189,414.

Specification of Letters Patent.

Patented July 4, 1916.

Application filed November 23, 1914. Serial No. 873,451.

To all whom it may concern:

Be it known that I, ARTHUR E. WELLS, a subject of the King of Great Britain, and resident of the city of Toronto, county of York, Province of Ontario, in the Dominion of Canada, have invented certain new and useful Improvements in Stair Constructors, described in the following specification and illustrated in the accompanying drawings, 10 that form part of the same.

The principal objects of the invention are, to devise a novel form of structure for a steel clad stair construction which will be very strong, may be manufactured at comparatively low cost, is easily and quickly assembled and may be packed for transportation in a very limited space, thus effecting a great saving.

The principal feature of this invention 20 consists essentially in the arrangement of a plurality of units to extend between the side strings forming a plurality of troughs adapted to receive a filling of suitable plastic material.

25 In the drawings, Figure 1 is a sectional elevational view through a portion of a stair constructed in accordance with this invention showing one of the treads filled with the plastic material. Fig. 2 is a sectional elevational view of a slight modification in the form of the units. Fig. 3 is a front sectional elevational view on the line *a—b* of Fig. 1.

Like numerals of reference indicate corresponding parts in each figure.

Referring to the drawings, 1 are the side strings of the stair case which may be of any suitable design and are provided with inwardly extending horizontal flanges 2 here 40 shown at the bottom edge such flanges being formed integral with the side strings or separate therefrom as may be desired.

In the form of the invention illustrated in Fig. 1, 3 are the step sections, here shown 45 formed of a riser portion 4 having a suitable nosing 5 at the top and shaped at the lower end with an obtuse angularly inclined portion 6 and a bottom or soffit portion 7 arranged preferably at right angles to the portion 6 and in an acute angular relationship to the riser 4.

The soffit portion 7 is adapted to overlap and rest upon the inturned edge flanges 2 of the side strings 1 and is secured thereto by 55 means of suitable bolts or rivets 8. The upper edge of the soffit portion 7 is bent up-

wardly at right angles thereto forming a flange 9 adapted to fit snugly against the angularly set portion 6 of the adjacent step section and the said flange is secured to the adjacent section by suitable bolts or rivets 10.

The step sections thus formed comprise trough shaped members closed at the ends by the strings which they abut and form a plurality of receptacles into which the cement or other plastic material to form the body of the step is placed. The risers 4 are supported adjacent to their upper edges by suitable brackets 11 secured to the inner side of the risers and to the side strings 1 and where desirable in steps of considerable width, braces 12 may be provided to reinforce the riser plates mid-way of their width, said braces being secured to the inner side of the riser and to the soffit plate 7 by suitable bolts or rivets.

In the form shown in Fig. 2, the soffit plate 13 forms part with the riser but is bent downwardly therefrom at an obtuse angle instead of upwardly as shown in Fig. 1. 80 When constructed in this form the plates are lapped the one over the other successively as shown and secured together by the bolts 14, the side edges being secured to the side flanges 2 of the strings 1 in the same manner as the structure shown in Fig. 1.

Two forms or methods of carrying this invention into effect are herein shown and described but it must be understood that other modifications in the actual construction of the individual trough shaped members may be made without departing from the spirit of the invention so long as a portion of each of the trough-shaped members is arranged in a common plane to form a continuous under-surface or soffit.

In a stair construction such as described the separate treads may be formed up in the shops and being of a trough or angle shaped section, they may be nested together and thus occupy very little space for transportation purposes. The parts are easily assembled as it is simply necessary after the placing of the strings to place the trough-shaped members in place upon the flanges 2 securing them in position and building up the successive steps in rotation and when all are assembled and secured together a very strong and durable stair frame or shell is provided.

What I claim as my invention is:—

1. A stair construction, comprising, side

- strings having inwardly turned longitudinal flanges, and a plurality of individual plate members supported upon said flanges and adapted to be secured together to form a continuous soffit, each of said plate members having an upwardly turned portion forming the stair risers and pockets to receive a filling of suitable material to form the treads.
10. 2. A stair construction, comprising, side strings, having inwardly extending longitudinal flanges, and a plurality of trough shaped plate members bent into angle formations and having sloping bottoms forming the stair soffit, the upper edge of said trough shaped members being bent upwardly at about a right angle to the soffit and adapted to engage a correspondingly bent portion of the riser of the adjacent member, said trough members being supported at the ends upon the flanges.
15. 3. A stair construction, comprising, side strings, having inwardly extending longitudinal flanges, trough shaped plate members, having perpendicularly arranged risers and bottoms sloping upwardly in acute angular relation to the risers adapted to rest upon the string flanges and to form the soffit, the upper edge thereof being turned inwardly to abut the adjacent member.

Signed at the city of Toronto, county of York, Ontario, Canada, this 19th day of Nov. 1914.

ARTHUR E. WELLS.
